Sinclair Refining Company, New York, N. Y.,
a corporation of Maine

Application May 25, 1932, Serial No. 613,574

2 Claims. (Cl. 158—4)

This invention relates to improvements in burners for supplying heat to heat absorbing surfaces arranged in a heating chamber elongated on the axis of the burner. The invention provides, particularly, improved control of flame configuration along the axis of the burner through the heating chamber.

The control of flame configuration in heating chambers so arranged is important in several respects, including the maintenance of conditions requisite for high combustion efficiency, the full utilization of the capacity of the heating apparatus and the elimination of maladjustments of the heat absorption by different parts of the heating surfaces. In heating apparatus in which petroleum oils are heated to temperatures upwards of about 700° F., the control of flame configuration becomes doubly important as the elimination of local overheating is peculiarly essential in such apparatus. The improved burner of the invention is of general application, but it is of special value and application in heating apparatus in which petroleum oils are heated to such temperatures.

With the improved burner of the present invention, the flame configuration along the axis of the burner through the heating chamber is controlled by independently moving, first, a baffle interposed in the throat of the burner between the point at which air for combustion is admitted to the throat and the point at which fuel is injected, and, second, the point of fuel injection. The improved burner of the invention comprises a burner throat communicating with the heating chamber, means for admitting air to the burner throat, means arranged axially within the burner throat for injecting fuel into the heating chamber through the throat at a point between the air admitting means and the heating chamber proper, an annular baffle positioned around the fuel injecting means between the point of fuel injection and the point of air admission and means adapted to hold or permit independent adjustment of the point of fuel injection i. e. the fuel injection nozzle, and the baffle along the axis of the burner. The burner throat is, with advantage, enlarged in section as it approaches the heating chamber, such enlargement cooperating with the controllably positioned baffle and point of fuel injection to afford further control of flame configuration.

The invention will be further described in connection with the accompanying drawings which illustrate, in some detail, one embodiment of the improved burner of the invention. It will be

understood that the invention is not limited to the particular burner illustrated in the accompanying drawing. In the accompanying drawing, Fig. 1 illustrates, in elevation and in section, a burner embodying the invention as arranged in conjunction with heating apparatus in which the heat absorbing surfaces are arranged in a heating chamber elongated on a vertical axis, the burner being arranged for down-draft firing, the heating apparatus other than the burner being illustrated conventionally, in fragmentary section, and Fig. 2 is an enlarged detail of the fuel injection nozzle of the burner illustrated in Fig. 1.

The heating apparatus illustrated in the drawing comprises a heating chamber 4, elongated on its vertical axis and laterally bounded by a cylindrical wall 5, and a series of tubes or pipes 6, through which the material to be heated is circulated, radially spaced from the axis of the cylinder and adjacent the cylindrical wall 5. The burner, positioned above the heating chamber 4 and co-axially therewith, communicates with the heating chamber through the roof 7.

The burner illustrated comprises a burner throat communicating with the heating chamber 4, this burner throat including a ring member 8 and a refractory passage 9 connecting the passage through this ring member with the heating chamber, the burner throat enlarging in section as it approaches the heating chamber, an annular opening 10 between the upper end of the ring member 8 and the cover and cover support members 11 and 12, dampers 13 in the form of annular segments arranged about and adapted collectively to cover the opening 10, a plurality of rods 14 supporting the dampers 13 and adapted independently to position these dampers, severally, with respect to the annular opening 10, a fuel injection nozzle 30 arranged axially within the burner throat on the end of a supporting tubular member 31, an annular baffle 32 positioned around the tubular member 31 and carried by a supporting tubular member 33, a clamp collar 34 supported by the cover member 11 and adapted to permit adjustment of the baffle 32 along the axis of the burner between the annular opening 10 and the fuel injection nozzle 30, and a clamp collar 35 supported by the tubular member 33 and adapted to permit independent adjustment of the fuel injection nozzle 30 along the axis of the burner. Oil, supplied through connection 23, atomized with steam supplied through connection 24, is injected through the nozzle 30. Assuming the clamp collar 34 to be released, the tubular mem-

ber 33 can be moved therethrough along the axis of the burner to be clamped in any chosen position, and, assuming the clamp collar 35 to be released, the tubular member 31 can be moved 5 through the tubular member 33 and the clamp collar 35 along the axis of the burner to be clamped in any chosen position independently of the position of baffle 32. The flame configuration in the heating chamber 4 can thus be closely 10 controlled by joint but independent regulation of the point of fuel injection along the axis of the burner and the position of the baffle 32 between the point of fuel injection and the point at which air is admitted to the burner throat. This control is improved by the provision, as in the burner 15 illustrated, of a burner throat enlarging in section as it approaches the heating chamber.

The dampers 13 and the means for independently positioning these dampers with respect to 20 the annular opening 10, in the burner illustrated, are described more particularly in an application filed June 2, 1932, Serial Number 614,986, by William R. Argyle and William J. Taylor. A perforated hollow ring 26 may be provided for the 25 supplementary introduction of gaseous fuel, supplied from connection 27 through branch connections 28.

The invention provides for control of the flame configuration within the heating chamber by provision of an annular baffle between the point of air admission and the point of fuel injection in the burner throat coupled with the provision of means for independently positioning this baffle and the fuel injection nozzle along the axis of 30 the burner. The control afforded is particularly useful in accommodating the heating apparatus to operations varying with respect to capacity rate. With the improved burner of the invention, flame configuration can be controlled, to secure 35 maximum combustion efficiency or to minimize risk of local overheating, more or less independently of the rate of firing. Similar flame configurations can be secured with widely different rates of firing and very different flame configurations can be secured with similar rates of firing. 40

I claim:

1. In a burner for supplying heat to heat absorbing surfaces arranged in a heating chamber elongated on the axis of the burner, in combination, a burner throat communicating with said 45

heating chamber and means for admitting air thereto, an axially movable tubular member supported so that its axis coincides with the axis of said burner throat, an annular baffle rigidly mounted on and extending outwardly from said tubular member, said annular baffle being disposed within said throat between said air admitting means and said chamber, adjustable means for holding said tubular member at any point along the axis of the burner throat to permit changing axially the position of said baffle, axially movable means for injecting fuel into said chamber arranged within said throat and extending through said baffle and said tubular member and substantially closing the latter, said means terminating in a fuel-injection nozzle, and adjustable means for holding said fuel-injecting means at any point axially with respect to said tubular member, whereby the longitudinal positions of the fuel-injection nozzle and of said annular baffle along the axis of the burner may be changed independently. 10 15 20

2. In a burner for supplying heat to heat absorbing surfaces arranged in a heating chamber elongated on the axis of the burner, in combination, a burner throat communicating with said heating chamber and enlarging in section as it approaches said chamber, means for admitting air to said throat, an axially movable tubular member supported so that its axis coincides with the axis of said burner throat, an annular baffle rigidly mounted on and extending outwardly from said tubular member, said annular baffle being disposed within said throat between said air admitting means and said chamber, adjustable means for holding said tubular member at any point along the axis of the burner throat to permit changing axially the position of said baffle, axially movable means for injecting fuel into said chamber arranged within said throat and extending through said baffle and said tubular member and substantially closing the latter, said means terminating in a fuel-injection nozzle, and adjustable means for holding said fuel-injecting means at any point axially with respect to said tubular member, whereby the longitudinal positions of the fuel-injection nozzle and of said annular baffle along the axis of the burner may be changed independently. 25 30 35 40 45
